UNITED STATES PATENT OFFICE

2,459,932

SILENT KEY MECHANISM FOR
TYPEWRITERS

Peter F. Gattuso, Chicago, Ill., assignor to Woodstock Typewriter Company, Woodstock, Ill., a corporation of Illinois

Application October 25, 1944, Serial No. 560,224

13 Claims. (Cl. 197—83)

1

This invention relates to typewriters in general and particularly to a key control means for typewriters. More specifically, the invention relates to means associated with a typewriter to effect or produce diacritical marks, signs or symbols for letters produced by depressing a typewriter key.

Typewriters in use in the United States are more or less standard in that the letters and symbols used in writing words are substantially the same, while certain letters in writing words in a foreign language must be accented or otherwise marked or symbolized to give the proper phonetics to certain letters. The umlaut is frequently used in the German and Swedish languages, while the circumflex accent, originally used in Greek over long vowels to indicate a rising or falling tone, is now used in other languages in phonetic notation to indicate special sounds. Other diacritical marks are used in French, Italian and other foreign languages to give a special sound or accent to a letter or for indicating an accent to a word. Typewriters for use in foreign languages usually have a keyboard with provision for diacritical marks, signs or symbols, but it is desirable that the standard American typewriters be provided with means so that a standard keyboard can be converted to use in writing foreign languages. It is, therefore, the primary object of the present invention to provide a typewriter with new and novel means for providing diacritical marks for foreign language typewriting as well as to provide novel and improved means for converting a standard typewriter into a foreign language typewriter.

Another important object of the present invention is the provision of new and novel means for rendering the escapement mechanism of a typewriter inoperative upon the depression of a typewriter key but maintaining the ribbon control and feed operative.

A further object of the invention resides in the provision of improved means for causing diacritical marks or other matter, or type on the type bar to strike the platen for writing or impression purposes without causing spacing of the carriage or platen.

A still further object of the invention is the provision of novel means in the form of an attachment applied to a functioning part of a typewriter for causing type to be printed but without advancement of the carriage or platen.

Still another object of the invention is the provision of a device or part adapted to be removably applied to a typewriter having a so-called

2

standard keyboard to convert the standard keyboard typewriter into a foreign language typewriter by rendering one or more keys dead by preventing operation of the carriage escapement mechanism but still permitting operation of the ribbon mechanism when a typewriter key is depressed for printing purposes.

Numerous other objects and advantages will be apparent throughout the specification which follows.

The accompanying drawings illustrate a selected embodiment of the invention and the views therein are as follows:

Fig. 1 is a detail perspective view of some of the parts of a typewriter disclosing some of the ribbon operating mechanism, certain parts being omitted for the sake of clearness;

Fig. 2 is a detail view on the line 2—2 of Fig. 5 showing the attachment applied to the lower U bar with a tooth of the U bar bent down so as to cause operation of the ribbon mechanism without operating the escapement mechanism, the key lever being not depressed;

Fig. 3 is a view similar to Fig. 2, with the key lever depressed causing operation of the ribbon mechanism but preventing operation of the escapement mechanism;

Fig. 4 is a detail perspective view of the attachment and embodying the invention; and

Fig. 5 is a bottom plan view of the lower U bar of a typewriter and embodying the invention.

The particular typewriter herein shown for the purpose of illustrating the present invention is the popular, well known "Woodstock" typewriter, although the invention is not confined to this particular make of typewriting machine.

The typewriter 1 includes a support and casting 2, part of which is broken away and other parts being shown in dotted position. Mechanism for operating the escapement and ribbon mechanism so far as affecting the invention is shown in full lines. A lower U-shaped bar 3 for operating and controlling the operation of the ribbon mechanism and the escapement mechanism is supported on brackets 4 (Fig. 1) which are secured to a cross rod 5. The cross rod 5 is pivotally mounted in end brackets 6, 6 which are secured to a part of the typewriter frame 2.

Spring means are provided to maintain the lower U-shaped bar 3 in normal upper position, as shown in Figs. 1 and 2, but permitting downward swinging movement upon the depression of a key lever 7 (Fig. 1), the key lever 7 having an operating lower surface 8 which is adapted to engage

alternately spaced long and short teeth 9 and 10 of the lower U-shaped bar 3, there being a key lever 7 for each tooth 9 and 10. The key lever 7 is depressed so as to bring the type on the type bar into printing engagement with the paper on the platen through the ribbon 11 (Fig. 1). The lower U-shaped bar 3 is moved upon the depression of the key lever 7 to operate the ribbon mechanism and to operate the escapement mechanism so as to move the platen one space, conforming to a letter being printed. The U-shaped bar, when being depressed by a key lever 7, also raises the ribbon 11 to bring it into proper alignment with the type on the type bar, and also causes the ribbon 11 to be fed a distance equal to one space so that the next succeeding key will print through a fresh part of the ribbon 11.

The invention has to do with rendering a key dead, that is, to permit the type controlled by the key lever 7 to be printed but preventing the carriage from being shifted, but permitting the ribbon to be raised and to be fed in the usual manner. The purpose of the invention is to cause a diacritical mark to be printed without shifting the platen and the carriage upon which the platen is supported so that when a letter to be printed is to be modified by the diacritical mark, the diacritical mark will be in its proper position with respect to the letter which is to be modified or accented, whereby it is not necessary for the operator to shift the carriage back so as to bring the diacritical mark or other symbol into proper position with respect to the letter to be printed. The invention, therefore, prints a diacritical mark at a predetermined position when the key lever is depressed, but prevents operation of the platen, whereby the letter to be modified or accented by the diacritical mark is printed at the same predetermined position upon the depression of the key lever controlling the letter on the type bar to be printed, whereby the letter will be positioned properly with respect to the diacritical mark and the carriage will be caused to be shifted in the usual manner by the depression of the letter. A key lever 7, carrying a diacritical mark on the co-operating type bar, is first depressed to print the diacritical mark, whereupon a second key lever 7 carrying the letter to be accented or modified, is next depressed, whereupon the diacritical mark and the letter will be printed in the same letter space. The depression of a lever carrying a diacritical mark will not cause the carriage to be shifted, but the letter which is to be modified or accented by the diacritical mark will be printed directly below the diacritical mark, whereupon the carriage will be shifted in the usual manner.

The ribbon mechanism, which includes means for raising the ribbon as well as feeding the ribbon, is controlled by the operation of a key lever 7, whether the key lever controls a diacritical mark or whether the key lever controls the letter which is to be accented by the diacritical mark. Therefore, the depression of a key 7 will cause the ribbon to be raised and the ribbon to be fed, whether or not the key carries a diacritical mark to be printed or a letter to be printed. However, during the printing of the diacritical mark the escapement mechanism is not controlled.

The means for controlling the raising and feeding of the ribbon 11 comprises spaced rods 12, 12. The lower end of each rod 12 passes through an opening 13 formed in the upper leg 14 of the lower U-shaped bar 3, as clearly shown in Figs. 2 and 3. A nut 15 is secured to the bottom end of each rod 12 and has free movement with respect to the

U-shaped bar 3. A key lever 7, in normal position and during normal operation, will assume the position shown in Fig. 2. That is, the upper end 14 of the U-shaped bar 3, upon which upper end 14 the teeth 9 and 10 are formed, will have a tooth underlying the operating part 8 of a key lever. A key lever 7, when depressed, will press downwardly on the upper part 14 of the U-shaped bar 3 and depress the U-shaped bar 3. The entire 10 U-shaped bar 3 is therefore moved on its pivot support 5, and inasmuch as the escapement mechanism is operatively connected to the U-shaped bar 3, the carriage will be shifted one space when a key lever 7 is completely depressed. 15 However, the depression of a key lever 7 and the moving downwardly of the U-shaped bar 3 will cause the rods 12 to be first shifted, whereupon the ribbon will first be raised and then fed, after which time the platen will be shifted one letter 20 space, all before the type on the type bar controlled by the key lever is brought into printing position with respect to the platen. The invention contemplates the raising and feeding of the ribbon, but preventing the operation of the escapement mechanism. Therefore, the escapement mechanism need not be described in connection with the present invention.

The mechanism for operating the ribbon both to raised position and for feeding the ribbon includes the rods 12, which are secured to the lower U-shaped bar 3, the ribbon feed, and two arms 16 (Fig. 1) which are adjustably secured to the ribbon feed rocker shaft 17 (Fig. 1). The depression of the key 7, therefore will depress the lower 30 U-shaped bar 3, and upon depression of the U-shaped bar 3 will oscillate the ribbon rocker shaft 17 by means of the connections 12 and 16. The oscillatory movement of the oscillating or rock shaft 17 causes the ribbon supporting element 18 to be raised in the usual manner by mechanism connecting the rock shaft 17 and the ribbon supporting frame member 18. This mechanism comprises a downwardly extending arm 19 (Fig. 1) operatively connected to the 35 vertically slidable ribbon raising frame 18, and pivotally connected at 20 (Fig. 1) to a gooseneck member 21. Therefore, when a key lever 7 is depressed, the ribbon supporting frame 18 will be caused to be raised to bring the ribbon into proper 40 position for printing purposes.

The rock shaft 17 also controls the feeding of the ribbon, and this ribbon feed mechanism comprises a feed pawl 27 and a holding pawl 28, the feed pawl 27 being controlled by an arm 29 (Fig. 1) fixed to the rock shaft 17. The rocking of the shaft 17 thus causes the feed pawl 27 to feed the ratchet 30 (Fig. 1) a space equal to one tooth on the ratchet. The ratchet 30 is mounted on a shaft upon which there is supported a ribbon spool 31 so that when the ratchet wheel 30 is rotated, the ribbon 11 is caused to be wound on the spool. Of course, the typewriter includes mechanism for reversing the feed of the ribbon, as there are two spools 31 and double ratchet operating mechanism 27-30. Means are also provided for effecting the reverse movement of the feed mechanism so that when the ribbon is near its end, the feed will reverse. However, the reversing feed of the ribbon does not constitute a part of the invention except insofar as the feed of the ribbon is concerned, regardless of the direction in which the ribbon moves during feed. The raising of the ribbon and the feeding thereof is primarily caused by the depression of a key 7 causing the downward movement of the U-

shaped bar 3. However, the invention causes the ribbon to be fed independently of the U-shaped bar 3, and the means for causing the ribbon to be raised and fed independently of the U-shaped bar comprises an implement or attachment 32 ⁵

While the attachment 32, when applied in operating position, may cause the U-shaped bar to be somewhat depressed, the U-shaped bar 3 will not be depressed a distance sufficient to cause operation of the escapement mechanism. However, a partial depression of the U-shaped bar may be effected during the depression of the key. Such partial depression of the U-shaped bar will in no wise effect the operation of the escapement mechanism, as the attachment 32 is adapted to co-operate with the rods 12 for operating the mechanism and while during normal operation, without the attachment, the U-shaped bar controls the operation of the ribbon mechanism, the attachment effects the operation of the ribbon mechanism somewhat independently of the U-shaped bar. Therefore, the invention has to do with the operation of the ribbon mechanism without movement of the bar 3 a distance sufficient to operate the escapement mechanism. Therefore, the invention as applied to the ribbon feed mechanism may cause the operation of the ribbon mechanism independently of any movement of the U-shaped bar or by co-operation with a slight downward movement of the bar, the size and construction of the U-shaped bar determining whether or not there will be any movement of the U-shaped bar for controlling the ribbon feed mechanism when the attachment is applied. Even though the attachment is positioned within the confines of the U-shaped bar 3, therefore, the U-shaped bar, for all practical purposes, has no bearing upon the operation of the ribbon feed mechanism when the invention is in place.

The U-shaped bar 3 comprises the upper arm or end 14, carrying the teeth 9 and 10, and a lower arm 33, the arms 14 and 33 being connected integrally by the side part 34. The lower U-shaped bar 3, therefore, is in the form of a channel, the upper arm 14 being longer than the lower arm 33, the upper arm carrying the spaced teeth 9 and 10. The lower arm 33 of the U-shaped bar 3 is provided with spaced notches 35 (Figs. 2 and 3) to permit the lower nuts 15, on the rods 12, to pass downwardly a sufficient distance to permit proper operation.

The normal position of the teeth 9 and 10 is shown in full lines in Figs. 1 and 2, and partly in dotted lines in Fig. 3. However, should a tooth 9 or 10 be bent downwardly from the normal plane shown in dotted lines in Fig. 3 to the position shown in section in that same figure, the depression of a key 1 will have no effect on the ribbon mechanism nor the escapement mechanism, and the key is what may be termed a "dead" key, that is, the type carried on the type bar controlled by this key 1 will be caused to be imprinted, but the ribbon mechanism and the escapement mechanism will not be operated.

The application of the attachment or implement 32 (Fig. 4) will cause the ribbon mechanism to be operated when a key is depressed but the escapement mechanism will not operate. The attachment 32 comprises an elongated body 36 provided with openings 37 therethrough, spaced apart a distance equal to the spacing of the rods 12 so that the rods 12 may pass therethrough. The ends of the rods 12 may be sufficiently threaded to permit the application of a second nut 38,

as shown in Figs. 2 and 3, so that the attachment 32 may be secured in position between the nuts 15 and 38 and between the legs 14 and 33 of the U-shaped member 3, as clearly shown in Figs. 2 and 3. The attachment 32 is provided at one end with an enlargement 39 having outwardly projecting spaced teeth 40, there being the same number of teeth 40 as there are keys carrying the diacritical marks. The attachment 32 is adapted to be positioned on the ends of the rods 12 after the teeth 9 and 10 are bent downwardly, with a tooth 40 bent upwardly, as clearly shown in Figs. 2 and 3, so that its upper edge may lie in contact with, or substantially in contact with, the lower operating part 8 of a key lever 7. With a tooth 9 or 10 bent downwardly, as shown in Figs. 2 and 3, and a tooth 40 of the attachment 32 bent upwardly, as shown in those same figures, the depression of a key 1 will cause the rods 12 to be moved downwardly independently of any movement of the U-shaped bar 3 and, therefore, the ribbon mechanism will be operated but the escapement mechanism will be prevented from being operated. Fig. 2 shows the attachment applied in position to the lower U-shaped bar 3, but the key 1 not depressed. The depression of the key 1 will cause the operating part 8 of the key lever 7 to engage the up-turned finger or tooth 40 on the attachment 32, and pull the rods 12 downwardly, as shown in Fig. 3. Thereupon, the rock shaft 17 will be operated to effect the raising movement of the ribbon as well as feeding the ribbon, but the U-shaped bar 3 will either be not operated at all or shifted a distance insufficient to operate the escapement mechanism.

The attachment 32 is preferably stamped from a single piece of sheet material, preferably being stamped in one piece with the number of spaced teeth corresponding to the number of keys carrying the diacritical marks. Therefore, if only one diacritical mark is required, only one tooth or finger 40 need be provided. If more than one tooth is required, the attachment 32 may have additional teeth or fingers 40. However, the attachment 32 may carry several teeth, but they may be rendered inoperative by keeping them in a sufficiently lower plane, that is, if the teeth 40 are not bent up a sufficient distance, as shown in Figs. 2 and 3, they will have no effect during the normal operation of the typewriter. Therefore, the number of bent-up teeth on the attachment determines which key, when depressed, will not effect the operation of the escapement mechanism. Even though the attachment may have innumerable teeth, they will have no bearing on the operation of the machine unless they are bent up or positioned in a plane so as to be engaged by a key to cause the operation of the ribbon feed mechanism.

60 The invention is hereby claimed as follows:

1. In a typewriting machine having ribbon feeding mechanism and escapement mechanism, a depressible bar for effecting operation of only the said ribbon feeding mechanism, an operative connection between the said bar and the ribbon feeding mechanism, whereby the latter will be actuated upon the depression of said bar by an actuating key, a second depressible bar for effecting operation of the escapement mechanism, and means whereby upon its depression by an actuating key, the said second depressible bar will also, through the medium of the first said bar, effect operation of the ribbon feeding mechanism.

2. In a typewriting machine having ribbon feeding mechanism and escapement mechanism,

a depressible bar for effecting operation of only the said ribbon feeding mechanism, an operative connection between the said bar and the ribbon feeding mechanism, whereby the latter will be actuated upon the depression of said bar by an actuating key, a second depressible bar for effecting operation of the escapement mechanism, and means whereby upon its depression by an actuating key, the said second depressible bar will also, through the medium of the first said bar, effect operation of the ribbon feeding mechanism, the first said bar having a predetermined degree of movement independently of the movement of the second said bar.

3. In a typewriting machine having ribbon feeding mechanism and escapement mechanism, a depressible bar for effecting operation of only the said ribbon feeding mechanism, an operative connection between the said bar and the ribbon feeding mechanism, whereby the latter will be actuated upon the depression of said bar by an actuating key, a second depressible bar for effecting operation of the escapement mechanism, means whereby upon its depression by an actuating key, the said second depressible bar will also, through the medium of the first said bar, effect operation of the ribbon feeding mechanism, and fingers on each of said bars, to be engaged by the respective actuating keys, said fingers adapted to be deflected into set positions with relation to the respective bars and the respective actuating keys.

4. In a typewriting machine having ribbon actuating mechanism and escapement mechanism, a first depressible bar for effecting operation of the escapement mechanism, a second depressible bar for effecting only the operation of the ribbon actuating mechanism, keys for actuating said bars, a connection between the said second bar and said ribbon mechanism, and a one-way connection between the first said bar and the second said bar, whereby upon depression of the second said bar by an actuating key, said ribbon actuating mechanism will be operated independently of the escapement mechanism, and upon depression of the first said bar the said second bar will also be actuated to operate both the ribbon mechanism and the escapement mechanism.

5. In a typewriting machine having ribbon actuating mechanism and escapement mechanism, a depressible bar for effecting operation of the escapement mechanism, a second depressible bar for effecting only the operation of the ribbon actuating mechanism, keys for actuating said bars, a connection between the said second bar and said ribbon mechanism, a one-way connection between the first said bar and the second said bar, whereby upon depression of the second said bar by an actuating key, said ribbon actuating mechanism will be operated independently of the escapement mechanism, and upon depression of the first said bar the said second bar will also be actuated to operate both the ribbon mechanism and the escapement mechanism, and fingers on the first said bar adapted to be selectively set into and out of operative position with respect to the bar and the actuating keys.

6. In a typewriting machine having ribbon actuating mechanism and escapement mechanism, a depressible bar for effecting operation of the escapement mechanism, a second depressible bar for effecting only the operation of the ribbon actuating mechanism, keys for actuating said bars, a connection between the said second bar

and said ribbon mechanism, a one-way connection between the first said bar and the second said bar, whereby upon depression of the second said bar by an actuating key, said ribbon actuating mechanism will be operated independently of the escapement mechanism, and upon depression of the first said bar the said second bar will also be actuated to operate both the ribbon mechanism and the escapement mechanism, and fingers on the second said bar adapted to be selectively set into and out of active position with respect to the bar and the respective actuating keys.

7. A typewriter having escapement mechanism, ribbon feeding mechanism, a depressible bar for effecting operation of the escapement mechanism, an attachment depressible with respect to said bar for effecting operation of only the ribbon feeding mechanism, keys for actuating said bar and attachment, an operative connection between said attachment and the ribbon feeding mechanism for actuation of said ribbon feeding mechanism upon depression of said attachment by an actuating key, and means operable upon depression of the bar by an actuating key and through the medium of the attachment for effecting also operation of the ribbon feeding mechanism.

8. A typewriter having ribbon feeding mechanism, escapement mechanism, a first depressible bar for effecting operation of only the ribbon feeding mechanism, a second depressible bar for effecting operation of the escapement mechanism, keys for actuating said bars, an operative connection between said first bar and the ribbon feeding mechanism for actuation of said ribbon feeding mechanism upon depression of said first bar by an actuating key, and means operable upon depression of the second bar by an actuating key and through the medium of the first bar for effecting also operation of the ribbon feeding mechanism, said second bar including a part normally engageable by a particular actuating key and capable of being conditioned to render said escapement mechanism inoperative when that actuating key is operated.

9. In a typewriter having ribbon raising mechanism, ribbon feeding mechanism, and escapement mechanism, a first depressible bar for effecting operation of only the ribbon raising and the ribbon feeding mechanisms, a second depressible bar for effecting operation of the escapement mechanism, a key lever for actuating said bars, operative connection between said first bar and the ribbon raising and the ribbon feeding mechanisms for actuation of said ribbon raising and feeding mechanisms upon depression of said first bar by the key lever, and means operable upon depression of the second bar by the key lever and through the medium of the first bar for effecting also operation of the ribbon raising and the ribbon feeding mechanisms, said second bar including a part normally engageable by the key lever and capable of being conditioned to render said escapement mechanism inoperative when said key lever is operated.

10. In a typewriter having ribbon raising mechanism, ribbon feeding mechanism, and escapement mechanism, a first depressible bar for effecting operation of only the ribbon raising and the ribbon feeding mechanisms, a second depressible bar for effecting operation of the escapement mechanism, a key lever for actuating said bars, operative connection means between said first bar and the ribbon raising and the ribbon feeding mechanisms for actuation of said ribbon rais-

ing and feeding mechanisms upon depression of said first bar by the key lever, and means operable upon depression of the second bar by the key lever and through the medium of the first bar for effecting also operation of the ribbon raising and the ribbon feeding mechanisms, said second bar including a part normally engageable by the key lever and capable of being conditioned to render said escapement mechanism inoperative when said key lever is operated, and said first bar having a finger constructed and arranged to be deflected into a set protruding position with respect thereto for engagement by the key lever when said second bar part is conditioned to render said escapement mechanism inoperative.

11. In a typewriter having ribbon raising mechanism, ribbon feeding mechanism, and escapement mechanism: a first depressible bar for effecting operation of only the ribbon raising and the ribbon feeding mechanisms, a second depressible bar for effecting operation of the escapement mechanism, key levers for actuating said bars, said second bar being capable of being conditioned to render said escapement mechanism inoperative in response to actuation of a particular key lever, operative connections between said first bar and the ribbon raising and the ribbon feeding mechanisms for actuation of said ribbon raising and feeding mechanisms upon depression of said first bar by a key lever, and means operable upon depression of the second bar by a key lever and through the medium of the first bar for effecting also operation of the ribbon raising and the ribbon feeding mechanisms, said first bar including a plurality of fingers constructed and arranged for adjustment to a position with respect thereto for engagement by a key lever when said second bar is conditioned to render said escapement mechanism inoperative in response to actuation of that key lever.

12. In a typewriter having ribbon raising mechanism, ribbon feeding mechanism, and escapement mechanism: a first depressible bar for effecting operation of only the ribbon raising and the ribbon feeding mechanisms, a second depressible bar for effecting operation of the escapement mechanism, key levers for actuating said bars, said second bar being capable of being conditioned to render said escapement mechanism inoperative in response to actuation of a particular key lever, operative connections between said

first bar and the ribbon raising and the ribbon feeding mechanisms for actuation of said ribbon raising and feeding mechanisms upon depression of said first bar by a key lever, and means operable upon depression of the second bar by a key lever and through the medium of the first bar for effecting also operation of the ribbon raising and the ribbon feeding mechanisms, said first bar being detachable and including a plurality of fingers thereon adapted to be bent to a predetermined position with respect thereto for engagement by a key lever when said second bar is conditioned to render said escapement mechanism inoperative in response to actuation of that key lever.

15 13. A typewriter having ribbon feeding mechanism, escapement mechanism, a key lever for operating said mechanisms, first means operable by the key lever engaging the same upon depression of the key lever normally to effect operation of the escapement mechanism, said first means embodying an element provided with a portion adapted to be selectively set to an inoperative condition with relation to the key lever, and second means operable by the key lever engaging the same upon depression of the key lever to operate only the ribbon feeding mechanism when the portion of said element is set to inoperative condition, said first means being connected with said second means for operating also therethrough the ribbon feeding mechanism upon depression of the key lever when the portion of said element is in operative condition with relation to the key lever.
